UNITED STATES PATENT OFFICE.

HENRY ARDEN, OF CINCINNATI, OHIO.

IMPROVEMENT IN HOT-AIR FURNACES.

Specification forming part of Letters Patent No. 74,270, dated February 11, 1868.

To all whom it may concern:

Be it known that I, HENRY ARDEN, of Cincinnati, Hamilton county, Ohio, have invented a new and useful Hot-Air Furnace; and I hereby declare the following to be a full, clear, and exact description thereof, reference being had to the accompanying drawing, making part of this specification.

My furnace is designed to secure the most useful and economical results in an air-heating furnace, by the slow combustion of a considerable bulk of fuel distributed over a large area of radiating-surface.

In the accompanying drawing, a furnace embodying my invention is shown, partly in elevation and partly in vertical section.

A is the base-wall, inclosing an ash-pit, B, which pit is traversed by a series of bars, C, that support a grate formed of separate bars, D. The sides of the ash-pit are sloped inward at their upper portion, so as to collect the ashes into a central trench of small dimensions, accessible by a door, P, of corresponding size. Rising vertically from and supported by the base A is the exterior wall or shell E, and concentrically within said shell a fire-chamber, F, which said shell and fire-chamber inclose between them an annular space, G, whose lower part has inlets H for cold air, and whose upper part has outlets I for air that has been heated by contact with the exterior surface of the fire-chamber.

H' is an annular deflecting sheet or plate, extending horizontally inward from the shell, just above the air-inlets H, and operating to force the cold air against the external sides of the fire-chamber, so as to take up all the available heat thereof, and to prevent the direct escape of the cold air into the warm-air pipes. The plate H' is also useful by producing an equal circulation or current of air on all sides.

Supported on columns J, or otherwise, in the center of the furnace, is a pier, K, preferably in the form of a truncated cone, as represented, and which, imparting an annular form to the fire-chamber, affords a large external radiating-surface for a given capacity of furnace. The fuel is introduced through openings L near the top of the fire-chamber, said openings having sloping spouts or throats L, to conduct the fuel across the annular space

G into the fire-chamber. Doors l serve to close the throats L, except at the instant of firing. The smoke escapes by a chimney, M, at the top of the fire-chamber.

N shows one of two similar doors for insertion and manipulation of the grate-bars. These doors are preferably of small height for their horizontal width, as represented, so as to prevent undue exposure of the furnace to sudden cooling, and also to avoid the danger of warping. These doors enable the fireman to shake down the ashes without materially opening the furnace.

O is a small registered draft-hole. The heated air is conducted wherever desired by pipes fitting on the necks of the outlets I.

One or more draft-tubes, Q, may be provided to increase the combustion. R is a pipe to contain water to be heated.

It will be seen that the pier K serves to displace the amount of coal which would otherwise uselessly occupy the center of the furnace. It will also be seen that my furnace is essentially air-tight and is adapted for the slow and protracted combustion of a large amount of fuel.

I claim herein as new and of my invention—

1. The provision, in an air-heating furnace, of the annular fire-chamber F, constructed as described, and provided with fuel-feeding passages L L', substantially as set forth.

2. The ash-pit B, with sloping sides and central trench, formed and arranged as described.

3. The arrangement of the air-heating furnace A B C D E, fire-chamber F, and imperforate central pier K, for the purpose explained.

4. In combination with the foregoing, the annular deflecting-plate H', with the air-inlet H and hot-air chamber G, as and for the purpose set forth.

5. The doors N N, formed and arranged as shown, in combination with the grate D and imperforate pier K, annular fire-chamber F, and draft-tubes Q, as set forth.

In testimony of which invention I hereunto set my hand.

HENRY ARDEN.
